DESIGN FOR A STORAGE BATTERY CASE

Julius J. Demko, Cleveland, Ohio, assignor to Willard Storage Battery Company, Cleveland, Ohio, a corporation of West Virginia

Application June 10, 1941, Serial No. 101,380

Term of patent 14 years

To all whom it may concern:

Be it known that I, Julius J. Demko, a citizen of the United States and a resident of Cleveland, in the county of Cuyahoga and State of Ohio, have invented a new, original, and ornamental Design for a Storage Battery Case, of which the following is a specification, reference being had to the accompanying drawing, forming a part thereof, in which

Fig. 1 is a perspective view of a storage battery case showing my new design;

Fig. 2 is an end elevational view; and

Fig. 3 is a top plan view.

I claim:

The ornamental design for a storage battery case, substantially as shown.

JULIUS J. DEMKO.
